U.S. Appl. No. 29/537,463, filed Aug. 26, 2015, Marsden.

Primary Examiner — Prabhakar Deshmukh

(74) *Attorney, Agent, or Firm* — Wolf, Greenfield & Sacks, P.C.

CLAIM

The ornamental design for a drawer latch, as shown and described.

DESCRIPTION

FIG. 1 is an top, front and right perspective view of a drawer latch showing my new design;

FIG. 2 is an exploded perspective view of FIG. 1;

FIG. 3 is a bottom, rear and right perspective view thereof;

FIG. 4 is an exploded perspective view of FIG. 3;

FIG. 5 is a bottom, front and right perspective view thereof;

FIG. 6 is an exploded perspective view of FIG. 5;

FIG. 7 is a top, rear and right perspective view thereof;

FIG. 8 is an exploded perspective view of FIG. 7;

FIG. 9 is a right side elevation view thereof;

FIG. 10 is an exploded right side elevation view of FIG. 9;

FIG. 11 is a left side elevation view thereof;

FIG. 12 is an exploded left side elevation view of FIG. 11;

FIG. 13 is a top plan view thereof;

FIG. 14 is a bottom plan view thereof;

FIG. 15 is an enlarged front elevation view thereof;

FIG. 16 is an exploded front elevation view of FIG. 15;

FIG. 17 is an enlarged rear elevation view thereof; and,

FIG. 18 is an exploded rear elevation view of FIG. 17.

The broken lines illustrate portions of the drawer latch that form no part of the claimed design.
